UNITED STATES PATENT OFFICE.

RICHARD GORNALL, OF BALTIMORE, MARYLAND.

CABLE RAILWAY.

SPECIFICATION forming part of Letters Patent No. 325,205, dated August 25, 1885.

Application filed March 3, 1884. Renewed July 28, 1885. (No model.)

To all whom it may concern:

Be it known that I, RICHARD GORNALL, of Baltimore, in the State of Maryland, have invented a new and useful Improvement in 5 Cable Railways; and I do hereby declare that the following is a full, clear, and exact description of the same.

My invention relates to cable railways, and is, for the greater part, applicable to railways 10 of that class in which the cable is located underneath the cars. It is shown in connection with the strap or band cable which has been heretofore described in an application filed in the United States Patent Office by me on 15 the 5th day of July, 1883, Serial No. 100,024.

The invention consists of improved mechanism for gripping the cable, improved mechanism for connecting the car to the gripping devices, a brake mechanism connected therewith, means for causing the gripping devices 20 to pass another cable of a crossing track, and an improvement in the band or cable itself.

The invention as embodied by me is shown in the accompanying drawings, in which Figure 1 is a longitudinal vertical section through car and track, showing the clutch and connecting devices in side elevation. Fig. 2 is a like section showing a crossing. Figs. 3, 4, and 5 show details on an enlarged scale, and 30 as hereinafter described. Fig. 6 is a section of part of the band or cable on line $x x$, Fig. 2, and Fig. 7 is a side elevation of the band without the lugs.

The car is of ordinary form, and runs on 35 ordinary surface rails, or on the rails of an ordinary elevated road, to which the invention is applicable, as well as to surface roads. The band A, which performs the office of a cable and may be properly so called, runs on 40 edge between supporting rollers, and is in construction, arrangement, and operation, with a single exception, hereinafter noted, the same as in the aforesaid application. It is slightly below the rails B, and runs continually in any 45 suitable channel, tube, or way. This should be open, as usual in this class of traction-ways, to receive the gripping device, which is shown at D. It consists of a flat bar, a , having spring jaws $x x$, adapted to pass over the edge 50 of the band-cables. The upper end is securely bolted in the forked end of the traction-bar C. Within the forks slide the side bars, $b b$, of a

compression or clamping frame. These side bars are forked below, as shown in Figs. 3 and 4, and the forked ends are connected by 55 bars $c c$, which are beveled to fit and wedge down upon and clamp the jaws of the gripping-bar a . In the cross-bar 6, which connects the upper ends of the side bars, $b b$, is set a pin, 7, which projects into a slot in a bell-crank lever, g , pivoted at h on the traction-bar C. The lower end of this bell-crank lever is connected to a rod, k , by means of which the clamp is worked. Obviously, when the rod k is drawn forward, the clamp will be 60 forced down upon the gripping-jaws and cause them to grip the edge of the band, reverse movement releasing the same. The traction-bar C is pivoted to a swivel, v , in the end of 65 a shaft, F, which has its bearings in the platform-guard. On the upper end of this shaft are pivoted the two levers n and o . The lever n is connected by rod m to bell-crank lever l on bar c , the other end of said bell-crank being connected to rod k , so that downward 70 movement of the lever n will cause the grip to take hold of the cable, and upward movement will release the same. The lever n is also connected to rod u , which extends to bar C, and is attached thereto by a bolt passing 75 through a slot in said bar. This permits downward movement of the lever n sufficient to apply the gripping device, but allows the lever to be raised and to lift the bar C. The lever o has a handle, p' , pivoted at 17, so 80 that it may be swung away from the handle p of lever n , or be laid close beside this handle. Then both may be grasped together, or one separately. The lever o is connected to the horizontal arm 8 of the bell-crank lever 85 3 by rod t , and thence by rod r connection is made to arm q of shaft which carries 90 brakes E. Lifting of lever o releases the brakes, and both levers being grasped and lifted at the same time, the grip is loosened 95 and the brakes applied. Further raising of lever n will cause the rod u to lift upon the bar C, and a catch, g , on rod u springs over 100 edge of platform and retains the bar with grip elevated clear of the cable, and which may be necessary in passing an obstacle.

In order to pass the cable of an intersecting line, I have provided automatic devices. In Fig. 2, L L represent the rails of a line

crossing the rails B, and A' is the band-cable. Suitably supported over the cable A, and in parallel vertical planes therewith, are guide-bars. There are four sets, of which only two are shown, those being two sets on each side of the cable, one inclining each way. The bars 11 are over the bars 10, and the space between is sufficient to receive the pins d and e of the gripping device. The ends of bars are bent, as shown at 12, to enlarge the opening and receive the pins, which, when the grip is on, are farthest apart. When the pins are brought together by the narrowing of the passage between the bars 10 and 11, the clamp 15 frame is lifted and the spring-jaws released. At the same time the whole gripping apparatus with its bar is raised, as shown in Fig. 2, so as to pass over the intersecting cable A', and it is gradually curved down on the other side by the set of bars inclined in the opposite direction. The sets of bars, as shown in Fig. 2, are separated by a space, Z, which permits the gripping mechanism of the intersecting road to pass. The gripper D is carried over this by means of its lower end riding upon the cable A'.

The cable is formed of the steel band, the lower edge of which is cut with rectangular holes 22. Into these are inserted blocks H, 30 having echeloned parts 11 and connecting-pieces 14, in width equal to thickness of the band, and in length the equal to length of the hole, or a little less, to allow the piece to be inserted. After insertion it is upset slightly 35 at 33 to hold it in place; but as the bearing on the cogs of the driver-wheel is at 4, the

strain tends to force the piece into place. The lugs 15 run in grooves of the pulleys, by means of which the cable is supported.

I claim as my invention—

1. The combination of the gripper D, bar C, swiveled to the front of the car-rod k, bell-crank levers g l, and a rod connecting the bell-crank lever l to the end lever, substantially as described.

2. The combination of the gripper D, the draft-bar C, the mechanism for operating the gripper connected to the lever n, and a rod, u, connecting the levers to the bar C, whereby the bar may be lifted and the gripper is released, substantially as described.

3. The combination, with the levers n o, with the rod t, connecting lever o with the brake mechanism, and with a rod connecting the lever n, of the gripping mechanism, the levers n and o being placed side by side, whereby the gripper may be released and the brake applied, substantially as described.

4. The combination, with the gripping mechanism provided with pins or rollers e d, of the incline bars 10 and 11, adapted to the intersecting cable A', substantially as described.

5. The combination, with the band-cable A', of the block H, constructed and applied to the band substantially as described.

In testimony whereof I have signed my name to this specification in the presence of two subscribing witnesses.

RICHARD GORNALL.
